M. BUCH,
FOLDING TOP FOR VEHICLES AND THE LIKE,
APPLICATION FILED MAY 27, 1918.

1,316,938.

Patented Sept. 23, 1919.

Inventor:

Max Buck,

by *John Middleton Donaldson & Son*
Atty's.

UNITED STATES PATENT OFFICE.

MAX BUCH, OF DETROIT, MICHIGAN, ASSIGNOR TO HENRY E. EDWARDS, OF JACKSON, MICHIGAN.

FOLDING TOP FOR VEHICLES AND THE LIKE.

1,316,938.

Specification of Letters Patent. Patented Sept. 23, 1919.

Application filed May 27, 1919. Serial No. 236,890.

To all whom it may concern:

Be it known that I, MAX BUCH, a subject of the Emperor of Germany, and a resident of Detroit, Michigan, have invented certain new and useful Improvements in Folding Tops for Vehicles and the like, of which the following is a specification.

My invention relates to improvements in folding tops for motor vehicles and the like and aims to provide an extremely simple and economical top which shall be self-supporting during its folding and projecting movements, thus enabling it to be operated easily by a single individual and the folds of the covering material to be properly arranged.

The invention also aims to provide a construction in which the main parts or elements will be all located in direct line or in the same plane with the main standard, reducing, as far as possible, the necessity of offset pivot connections and obviating the necessity of any lateral bends in the linkage arrangement.

With these and other objects in view the invention includes the novel features of construction and arrangement and combination of parts hereinafter described, my said invention being defined by the appended claims.

A top embodying my invention is illustrated in the accompanying drawing, in which,

Figure 1 is a side elevation showing the top in its extended position in full lines and in a partially folded position in dotted lines.

Fig. 2 is a perspective detail.

In Fig. 1 the top being shown in side elevation, only the standard bow arms, etc., on one side appear, but it will be understood that they are duplicated on the other side, only one side being shown for convenience of illustration.

Similarly, in the following description and claims, reference is made for convenience to the members on one side only and reference to one side is to be understood as including both sides.

In the drawing the numeral 1 designates the body of a vehicle for which the top is adapted and which is intended to be representative of any type of vehicle or motor boat, needing such a protective covering.

The top covering material is indicated at

2 supported by the folding frame herein-after described. This includes a main standard 3 designed to have its lower end pivotally supported in any suitable manner from the body of the vehicle, as indicated at 3^a, and designed to coöperate with the usual rear bow arm 4 which may be pivoted to the standard at 4^a. It will be obvious, however, that if desired the rear bow arm might be pivoted to the body and the standard to the bow arm or both might be connected to the same pivot 3^a, these being recognized equivalents. 5 designates the outrigger bow or arm thereof which has its rear end pivotally connected at 5^a at the front end of a link or member 9 pivotally connected in turn to the standard.

The front auxiliary or supplemental pivot supporting bow arm or member 7 is pivotally connected to the outrigger bow arm at 7^a and in the same plane therewith by means of an upstanding lug or lugs and this bow arm inclines rearwardly and upwardly from the outrigger bow arm in the extended and normal position of the parts as shown in full lines in Fig. 1. To the supplemental bow arm 7 is pivotally connected at 8^a the forward end of a link or member 8 which is in turn connected to the link 9 by a suitable pivot 9^a and is extended beyond said pivot 9^a and the extended end indicated at 8^b is pivotally connected by link 6 with the standard 3 at a point below the point of pivotal connection of the link 9 as indicated at 6^a. The link 9 is extended rearwardly of its point of pivotal connection 9^a with the standard and said extended part 9^x is adapted to form or carry a cover supporting bow arm. The outrigger bow arm 5, and the bow arm 7 and link 9 may be made wholly of metal and integral with the bows, thus forming an all metal construction.

My present arrangement, however, adapts itself especially for use in connection with wooden bows and to this end the outrigger bow arm 5, the bow arm 7 and the extended part 9^x, of the link 9, are made in the form of or provided with bow sockets for the reception of the arms or ends of wooden bows which are indicated respectively at W, W' and W².

The extended part 9^x, being in the form of the bow socket for a wooden bow, would necessarily be of material thickness. To

secure this in the most efficacious manner to the main standard, I cause it to extend across the top of the main standard in the same plane therewith and secure its under-
5 side to a socket or bracket member S having the part curved to fit the underside of the bow socket portion 9, and secured thereto in any convenient manner, as by riveting or welding, this bracket member having
10 two dependent lugs s embracing opposite sides of the standard or preferably a sleeve R on the upper end of the standard 3 and secured thereto by the rivet or pivot pin 9^a as shown in Fig. 2. By locating the ex-
15 tended part 9^a, in the same plane with the standard and the bow arms 5 and 7 in the same plane, it will be seen that only the links 6 and 8 are connected to the other parts and these in such a manner that no
20 lateral bends or offsets are required.

To limit the upward movement of the parts in the extension of the top I may provide a pin 10 on the link 9 which is adapted to contact with the underside of the link 8.

25 Having thus described my invention, what I claim is:-

1. In a folding top, a supporting standard, an outrigger bow arm, a link connecting the extremity of the outrigger bow arm
30 to the standard, a member pivoted to the outrigger bow arm and normally inclining rearwardly and upwardly, a second member pivotally connected to said first named member and to said link, one of said mem-
35 bers carrying a cover supporting bow, said second member having a part extended be-
yond its point of pivotal connection with

said link, and a link connecting said extension with the main standard, below the pivot point of the first named link, said 40 first named link having a part extended in rear of its point of pivotal connection with the standard to constitute a cover supporting bow.

2. In a folding top, a supporting standard, an outrigger bow arm, a link connecting the extremity of the outrigger bow arm to the standard, a bow arm pivoted to the outrigger bow arm and normally inclining rearwardly and upwardly a second link 50 pivotally connected to said bow arm and to said first named link, said second link having a part extended beyond its point of pivotal connection with the first link, and a third link connecting said extension with the main standard below the pivot point of the first named link, said first named link having a part extended in rear of its point of pivotal connection with the standard to constitute a cover supporting bow 60 arm.

3. In a folding top, a main standard, an outrigger bow arm, a link pivotally connected to said outrigger bow arm and extending across the top of the standard in 65 the same vertical plane, and a clip having a curved portion secured to the under side of said bow socket portion and a pair of spaced lugs depending from opposite sides of said curved portion and embracing the 70 standard and pivotally connected thereto.

In testimony whereof, I affix my signature.

MAX BUCH.
